UNITED STATES PATENT OFFICE

CLAUDE PENNINGTON, OF SAN DIEGO, CALIFORNIA, ASSIGNOR TO KOEHRING COMPANY,
OF MILWAUKEE, WISCONSIN, A CORPORATION

ACCELERATOR FOR POWER SHOVELS

Application filed December 26, 1929. Serial No. 416,675.

In the operation of excavating machines, particularly shovel cranes, it is often highly desirable, and at times even necessary, to accelerate the speed of the power source. This is particularly true during crowding out and boom hoisting operations of the dipper stick and boom respectively. Many devices for accelerating the speed of the power source in machines of this type have been devised although in most instances they are highly complicated.

An important object of the present invention is the provision of an accelerating device to be used in conjunction with the power source of an excavating machine, which device is marked by its simplicity.

Another objectionable feature to many of the present types of accelerator devices is the fact that they are under the manual control of the operator of the machine, thereby permitting such operator to accelerate the power source under conditions of no load, which is obviously a highly undesirable treatment of the power source.

A further object of my invention, therefore, is the provision of an accelerator device which is not under the manual control of the operator of an excavating machine but which acts incident to the operation of certain control instrumentalities therefor.

Going more into detail, I provide a cable or other flexible member which is connected at one end to the butterfly valve of the carburetor of the power source and also to the speed control means or governor. The other end of the flexible member is preferably connected to the reach rod controlling the action of the clutch device associated with either the boom hoist or dipper stick drums, or both. Of course, this end of the cable could be secured to the clutch itself or any other part of the control instrumentalities for the drums. In order to do away with the necessity of accurate adjustments of the cable, I preferably include therein an elastic member which in the present instance takes the form of a coil spring.

With these and other objects and advantages in view, the invention comprises certain other novel constructions, combinations, and

arrangements of parts as will be subsequently specified and claimed.

For a full and more complete understanding of the invention, reference may be had to the following description and accompanying drawing, in which—

Figure 1 is a perspective view bringing out my novel invention and showing the manner in which it is applied to an excavating machine.

Figure 2 is a diagrammatic showing of the invention and more clearly brings out the manner in which it is applied to an excavating machine.

Figure 3 is a perspective view showing the connection of the cable to the reach rod.

Figure 4 is a view in side elevation of the same, and

Figure 5 is a diagrammatic view showing the connection of the cable with the butterfly valve and the governor.

While a preferred specific embodiment of the invention is herein set forth, it is to be understood that I am not to be limited to the exact constructions illustrated and described, because various modifications of these details may be provided in putting the invention into practice within the purview of the appended claims.

In Figure 1 of the drawing the frame of an excavating machine denoted A carries a power source B and winding drums C, one for controlling operations of the boom and the other for controlling operations of the dipper stick. Clutches 1 for the drums C are operated by reach rods 2 which in turn are controlled by the usual levers as shown at 3. A bracket 4 is secured to each of the reach rods 2 in any preferred manner such as by the double nuts as shown at 5. One end of a cable 6 is secured to one of the brackets 4 by means of a hole 7 therein, the cable then passing over pulleys as shown at 8, the other end thereof being secured to the levers 9 and 10, which are connected to the butterfly valve 11 of the carburetor and the speed control means or governor 12 respectively. An elastic member such as the coil spring 13 is preferably inserted somewhere in the length of the cable 100

6 so as to do away with the necessity of accurate adjustments of the same.

As before pointed out, the device is very simple in nature, being practically foolproof, 5 and yet at the same time accomplishing a highly desirable result.

The operation of the device is thought to be obvious, but a short explanation thereof will now be given. Upon movement of either of 10 the levers 3 in a direction to cause downward movement of one of the reach rods 2, the cable 6 will be pulled so as to actuate the rods 9 and 10, which action causes an opening of the butterfly valve 11 and an operation of the 15 governor 12 so that the speed of the power source B is accelerated. Such a movement of the levers 3 is accompanied by either a boom hoisting or dipper crowding out action. Upon reverse movement of the levers 3 for 20 lowering the boom or racking in the dipper, which movements do not require such a great amount of power, the reach rods 2 will be moved upwardly causing a slack in the cable 6 and no actuation of the butterfly valve 11 or 25 the governor 12 will follow. It can thus be seen that a highly efficient yet simple accelerator device has been provided which is not under the control of the operator during conditions of no load. This accelerator device 30 operates incident to movement of the control instrumentalities in such a manner as to cause a load to be thrown upon the power source, for example, during boom hoisting or dipper stick crowding out.

35 From the foregoing, it will be seen that I have provided a simple but efficient accelerator which is automatically operable incident to the actuation of one of the control devices, especially one of the clutches. Such an accelerator is especially valuable since the same is not directly under the control of the operator of the excavating machine and is not operable independently of the aforesaid control devices.

40 Having thus-described my invention, what I claim as new and desire to secure by Letters Patent of the United States, is—

1. Excavating apparatus of the class described, comprising the combination with an excavating machine and a power source therefor provided with instrumentalities for accelerating the speed of the power source, of a control device comprising reach rods for 50 controlling one of the movements of the excavating machine, and accelerating means including flexible cables directly connected at all times to the reach rods of the control device and to the accelerating instrumentalities of the power source and automatically operable simultaneously with the operation of the control device for accelerating the rate of speed of the power source during the said movement.

55 2. Excavating apparatus of the class de-

scribed, comprising the combination with an excavator machine and a power source therefor provided with instrumentalities for accelerating the speed of the power source, of control levers for controlling the movements of the machine, reach rods operable by the levers, a flexible cable connected at all times directly to the reach rods and to the acceleration instrumentalities of the source of power, whereupon actuation of any one of the levers in a direction to impose a load upon the power source pulls upon the cable to automatically accelerate the speed of the power source, and tensioning means inserted in the cables to maintain the cables always under suitable tension.

3. An excavating machine of the class described, comprising, the combination with a source of power for the machine provided with instrumentalities for accelerating the speed thereof under load, of cable winding and unwinding instrumentalities actuated by the source of power, control mechanism for the said instrumentalities comprising clutches and clutch actuating devices, the said devices including clutch levers and reach rods interconnecting each clutch with its respective lever, a bracket on each reach rod, and a resiliently tensioned flexible cable secured to each bracket and to the speed accelerating instrumentalities of the power source, whereby upon actuation of the said clutches to operate the respective drums to thereby increase the load upon the source of power, the speed accelerating instrumentalities will be automatically operated to accelerate the rate of speed of the power source while under influence of the increased load.

4. An excavating machine of the class described, comprising, the combination with a source of power for the machine provided with instrumentalities for accelerating the speed thereof under increased load, of operative instrumentalities for the machine driven by the source of power and constituting increased load thereon during operation of the instrumentalities, devices for selectively bringing the said instrumentalities into and out of operative relationship with the source of power, and means including resiliently tensioned flexible cables connected with the speed accelerating instrumentalities and with the said devices for automatically accelerating the speed of the power source only upon engagement of the said operative instrumentalities with the power source with attendant increase in load upon the power source, the said cables being operative upon the power source only during the application of the increased load upon the power source.

In testimony whereof I affix my signature.

CLAUDE PENNINGTON.
